(57) **CLAIM**

The ornamental design for an acoustical barrier sound wall assembly, as shown and described.

DESCRIPTION

FIG. 1 is a top plan view of an acoustical barrier sound wall assembly, the bottom view being a mirror image thereof; FIG. 2 is a front elevational view thereof; FIG. 3 is a bottom plan view thereof; FIG. 4 is a rear elevational view thereof; FIG. 5 is a right-side elevational view thereof; FIG. 6 is a left-side elevational view thereof; FIG. 7 is a front isometric view thereof; FIG. 8 is a rear isometric view thereof; FIG. 9 is a top plan view of one acoustical barrier sound wall of the acoustical barrier sound wall assembly, the bottom view being a mirror image thereof; FIG. 10 is a front elevational view of the acoustical barrier sound wall of the acoustical barrier sound wall assembly seen in FIG. 9; FIG. 11 is a rear elevational view thereof; FIG. 12 is a right-side elevational view thereof, the left-side elevational view being a mirror image thereof; FIG. 13 is a front isometric view thereof; FIG. 14 is a rear isometric view thereof; and, FIG. 15 is a front isometric exploded view thereof, showing parts of the acoustical barrier sound wall of the acoustical barrier sound wall assembly unassembled.
